ORCHARD HEATER

Filed Sept. 6, 1927

UNITED STATES PATENT OFFICE.

RUDOLPH PETER, OF SAN JOSE, CALIFORNIA.

ORCHARD HEATER.

Application filed September 6, 1927. Serial No. 217,611.

This invention refers to orchard heaters of the oil burning type and has to do with vent arrangement and specific stack construction.

5 The objects of the improvements are to provide a better combustion and avoidance of draft trouble caused by wind.

In the drawings Fig. 1 is a vertical section of a complete orchard heater made in 10 accordance with my invention.

Fig. 2 is a plan view of the wind shield thereof.

Fig. 3 is an enlarged sectional detail of a modification in formation of the special 15 vents in the base of the stack; and Fig. 4 is a cross section of a portion of the stack constructed as per Fig. 3 broken away to show the form at A—A and B—B of Fig. 3.

In the drawings 1 is an oil pot as indicated. The pot is provided with a cover 2 20 fitting tightly thereover and having an upstanding neck 3 over which a stack is mounted, while upon the cover is arranged one or more adjustable air vents and filling opening as at 4. The oil when ignited 25 burns principally in the stack.

The stack comprises two stove pipe sections 5 and 6 of conical form and joined together at their large diameters preferably 30 by a simple telescopic joint as at 7.

The proportionate areas of the stack sections is important, the diameter of the top of the upper section being somewhat larger than the diameter of the lower end of the 35 lower section.

Around the base of the lower section are several rows of vents 8, 9, 10 staggered one above the other as indicated. These vents may be formed by cutting and bending small 40 flaps or ears of the metal inward as indicated at 8', 9' and 10' or may be formed as shown in Figs. 3 and 4 to be later described.

In either construction the lower vents 8 are relatively large elongated openings while 45 the vents 9 and 10 are very narrow slits as shown and staggered in vertical relation to one another as clearly shown in Figs. 1 and 4.

Around the lower part of the stack is a 50 curved U shaped sheet metal wind shield 11 forming a space or channel around the stack open on the ends of the U for wind blowing in one general direction toward the stack.

This U shaped guard rests upon the cover

2 of the oil pot and is retained in place 55 around the stack by a wire 12 passing from one leg of the U to the other and which wire holds the shield in place on the stack so that the shield may be revolved to point in any direction so that it may be set to catch the 60 prevailing wind.

In Figs. 3 and 4 a variation in construction of the lower end of the stack is shown and in which the stack 5' is formed with steps 13, 14, 15 with vents 13', 14', 15' passing 65 through the steps. Vents 13' and 14' are the narrow slits while vents 15' are the lower large vents corresponding to the large vents 8 of Fig. 1.

Steps or shoulders 13 and 14 being relatively small may be rolled into the metal of the stack section 5', but step 15 is best made on a separate section 5'' formed with outwardly bent ears 16 into which downwardly extending ears 17 of section 5' extend. 70 75

Ears 16 are preferably notched at XX (see Fig. 4) so that ears 17 will interlock in sliding section 5' vertically downward into position.

The special shape of the stack comprising 80 a pair of cones joined at their bases, and the arrangement of vents with staggered small slit-like vents above the larger openings, together with the larger diameter of the top of the stack over the extreme lower end has 85 been found after experiments with a great variety of forms, to result in a perfect combustion not otherwise attainable, and the shield 11 makes the combustion uniform at all sides of the stack as it prevents the formation 90 of a rarefied condition of the air on the offside which heretofore introduced an undesirable condition in the stack with consequent smoking and loss of efficiency.

The arrangement of vents due to the 95 downwardly decreasing size of the stack pipe results in the different rows of vents lying on concentric circles with the openings directed upwardly one within the other toward the center of the stack, an arrangement 100 105 which feeds air into the rising gases so as to form alternate rings therewith.

I claim:

1. An orchard heater comprising an oil pot surmounted by a stack, said stack comprising two frusto-conical sections directly joining at their large ends and with a small end connected to the pot and a small end

- at the extreme top of the stack of larger diameter than the extreme lower end of the lower section.
2. An orchard heater comprising an oil pot surmounted by a stack, said stack comprising two frusto-conical sections joined at their large ends and with a small end connected to the pot, a plurality of rows of air vents formed around the base of the stack 10 arranged in vertically spaced position and with the lower row comprising vents of greater area than the vents above, said stack having a free unobstructed passage throughout its perforated length.
- 15 3. An orchard heater comprising an oil pot surmounted by a stack, said stack comprising two frusto-conical sections connected at their large ends and with a small end connected to the pot, a plurality of rows of 20 air vents formed around the base of the lower section of the stack only, comprising transverse slits in the stack with the wall of the stack bent inwardly below each slit and slanting downwardly and outwardly.
- 25 4. In an orchard heater of the character described, a stack, a series of vents around the stack, and a shield around portion of the vents and stack spaced outwardly therefrom.
5. In an orchard heater of the character 30 described, a stack, a series of vents around the stack, and a shield around portion of the vents and stack spaced outwardly therefrom and open on one side for admission of lateral air currents.
6. In an orchard heater of the character 35 described, a stack, a series of vents around the stack, and a shield around portion of the vents and stack spaced outwardly therefrom, said shield comprising a U-shaped 40 sheet provided with means holding it in place around the stack.
7. In an orchard heater of the character 45 described, a stack, a series of vents around the stack, and a shield around portion of the vents and stack spaced outwardly therefrom, said shield comprising a U-shaped 50 sheet provided with means holding it in place around the stack, and the shield being revolvable around the stack for directing the legs of the U in various directions.

RUDOLPH PETER.
